CHAIR

Robert E. Kjer Jakobsen, Los Angeles, Calif., assignor
to Schlumberger Limited (Schlumberger N.V.), Hous-
ton, Tex., a corporation of the Netherlands Antilles

Continuation of design applications Ser. No. 974 and Ser.
No. 987, Feb. 9, 1966. This application May 10, 1967,
Ser. No. 7,337

Term of patent 14 years

(Cl. D15—1)

FIG. 1 is a side perspective view of a chair in accordance with my design;

FIG. 2 is a rear perspective view thereof;

FIG. 3 is a front perspective view thereof;

FIG. 4 is a front perspective view of a modified form of the chair of FIGURE 1;

FIG. 5 is a side perspective view of the chair embodiment shown in FIGURE 4; and

FIG. 6 is a rear perspective view thereof.

The design is characterized by a swing-like appearance produced by a single elongated rear leg support extending from the rolled-over top edge of the back rest to the valley of a U-shaped base portion, all as shown.

This application is a continuation of my earlier filed applications Ser. Nos. D. 974 and D. 987 filed Feb. 9, 1966, and now abandoned.

I claim:

The ornamental design for a chair, substantially as shown and described.
